UNITED STATES PATENT OFFICE.

CHARLES T. HOOKWAY, OF SYRACUSE, NEW YORK.

WHEEL-SHOVEL.

No. 870,172.

Specification of Letters Patent.

Patented Nov. 5, 1907.

Application filed January 24, 1907. Serial No. 353,924.

To all whom it may concern:

Be it known that I, CHARLES THOMAS HOOKWAY, of Syracuse, in the county of Onondaga, in the State of New York, have invented new and useful Improvements in Wheel-Shovels, of which the following, taken in connection with the accompanying drawings, is a full, clear, and exact description.

This invention relates to certain improvements in wheel-shovels adapted to be used for grading, excavating and fills and in other relations where it is desired to expeditiously load and convey limited quantities of earth or other material from one place to another over short hauls.

One of the objects of my present invention is to relieve the horses from excessive strain and mutilation by providing the supporting frame of the shovel with a forwardly extending reach bar and pivoting the front end of such reach bar directly to king-bolt of the front running gear to which the pole for the horses is connected in the usual manner for four wheeled vehicles.

A further object is to pass the reach between the upper and lower cross bars of the hounds of the front gear at the rear of the axle while the pole is attached in the usual manner to the front end of the hounds in front of the axle whereby the downward and rearward pull or resistance caused by drawing the front end of the shovel into the earth produces a downward pressure upon the rear ends of the hounds thereby tilting the front ends of said hounds and pole attached thereto upwardly and thus relieving the horses from such excessive load or resistance and also from the excessive vertical and lateral vibration of the shovel.

A still further object is to provide means under control of the operator from the seat of the vehicle whereby the shovel may be readily dumped without the aid of an extra employee.

Another object is to provide adjustable means for retaining the shovel in its digging position against over-turning as the vehicle is drawn forward in the act of loading.

In the drawings,—Figures 1 and 2 are respectively top plan and side elevation of a wheel-shovel embodying the various features of my invention, the wheels nearest to the point of view in Fig. 2 being removed. Fig. 3 is a perspective view of the detached shovel and axle showing the detent for preventing overturning of the shovel during the operation of digging. Fig. 4 is a side elevation of the rear portion of the shovel supporting frame showing the shovel in its dumping position in full lines and in its digging position by dotted lines. Figs. 5 and 6 are enlarged top plan & side elevation respectively of a portion of the detent and one of its supporting bars.

As best seen in Figs. 1, 2, and 4, the shovel as —1— is provided with opposite side straps —2— rigid

thereon and having their forward ends pivotally connected at —3— to the rear ends of the side bars —4— of a main supporting frame having a central lengthwise reach-bar or tongue —5—, the front end of which is passed between upper and lower cross bars —6— of the hounds —7— of a front running gear —8— and is pivotally connected to the king-bolt as —9— of said front running gear to permit the rear gear as the rear axle —10— and rear wheels —11— together with the shovel —1— and its supporting mechanism to shift from side to side while the cross bars —6— which engage the reach-bar —5— at the rear of the front axle as —12— serves to hold the shovel supporting frame against undue vertical movement and also relieves the pole as —13— from the excessive vertical and lateral vibrations and strains to which the shovel is subjected during the operation of digging or loading.

It will be seen upon reference to Figs. 1 and 2 that this pole —13— is connected in the usual manner to the front ends of the hounds in front of the axle —12— by means of a pivotal bolt —14— which permits vertical vibration of the hounds independently of the pole and thereby relieves the horses from excessive vibrations and strains to which the reach is subjected during the operation of loading.

Rigidly secured to the opposite sides of the shovel —1— are upright iron straps or hangers —15— which are securely connected at —16— at their upper ends to the front ends of a vertically rocking frame —17—, the latter being rigidly secured to the rear axle —10—. This rear axle constitutes a part of the frame —17— and its central portion is arched upwardly above the axis of the wheels —11— upon which axis the frame —17— swings.

The side bars of the frame —17— are united at the rear of the shovel to form a handle —18— by which said frame may be rocked vertically upon its axis as —19— which in this instance is coincident with axis of the wheels and owing to the fact that the shovel supporting hangers —15— are secured at —16— to the front end of the frame —17— in front of the axis —19— and between the latter axis and pivots —3— connecting the shovel to the rear ends of the frame bars —4—, by elevating the rear end of the frame —17— to the position shown by dotted lines in Fig. 4, the front or digging ends of the shovel will be tilted downwardly to the dotted position shown in said Fig. 4 in which position the bucket is held by a detent or catch —20— which is pivoted at —21— to the shovel —1— and is connected by a link —22— to the front end of the frame —17—, said link —22— serving to rock the catch —20— into engagement with a stirrup —23— on the main supporting frame as the front end of the shovel is thrown downwardly by the upward rocking movement of the rear end of the frame —17—.

As a further precaution against overturning of the

- shovel during the operation of loading, a pair of arms —24— are pivoted at their front ends to the upwardly arched central portion of the axle —10— and are provided with a cross bar —25— constituting a detent 5 adapted to drop by gravity into the rear end of the shovel to engage the inner face of the upper edge of said shovel and thereby brace the latter against upward and forward movement during the operation of digging.
- 10 The shovel is now in position to load by drawing the vehicle forwardly and as soon as loaded the frame —17— is returned to its normal position which elevates the shovel, the latter being held in this position by a detent —26—.
- 15 The general construction of the shovel and its supporting and tilting mechanism hereinbefore described except the detent consisting of the arms —24— and cross bar 25— for holding the shovel against overturning during the operation of loading is substantially the 20 same as what is commonly known as the "Syracuse wheel scraper" manufactured by the Syracuse Chill Plow Company, and therefore applicant does not herein claim the shovel and its operating mechanism hereinbefore described except as it enters into combination 25 with the connections with the front gear through the reach-bar —5— and also with the gravity detent —25— and the means controlled by the operator from the seat of the vehicle for dumping the shovel as will be presently described. This dumping mechanism consists 30 essentially of a cable —30— having its rear end passed over a sheave —31— on a bracket —32— on the rear axle and connected at —33— to the frame —17— or handle —18— while its front end is attached to a winding drum —34— provided with a ratchet wheel —35— 35 which is adapted to be engaged by a pawl —36— on a lever —37—, the latter being loosely mounted on the shaft of the drum —34— so as to be moved back and forth in winding the cable on said drum, said lever being located in proximity to a seat —38— which is 40 supported upon a spring arm —39— on the reach-bar —5—.
- The central portion of the cable —30— is guided on an intermediate sheave —40— which is supported upon a bracket —41— on the reach-bar. Mounted upon this 45 reach-bar is a catch —42— having its free end located in the path of the rear end of the frame —17— to engage the latter and hold it in its dumping position.
- Assuming that the shovel is in its normal up-position and empty and that it is desired to load the same, the 50 detent —26— is first detached by means of its hand piece as —26— after which the operator on the ground elevates the rear end of the rocking frame —17— thereby depressing the front end of the shovel to the position shown in dotted lines in Fig. 4 during which 55 operation, the upwardly arched central portion of the rear axle is thrown forwardly thereby drawing the arms —24— and connecting cross bar —25— in the same direction until the rear face of the cross bar drops automatically into the rear end of the shovel forming an engaging shoulder or detent for engaging the inner 60 face of the upper front edge of the rear end of the shovel and resisting any tendency of the shovel to overturn during the operation of locating, which is accomplished by drawing the vehicle forwardly over the 65 ground to be excavated.

As soon as the shovel is filled the rocking frame —17— is returned by the same operator to its normal position and locked in such position by the detent —26— whereupon the load may be conveyed to the desired locality where it is to be dumped.

As soon as the dumping ground is reached the operator or driver on the seat of the vehicle may operate the lever —37— backward and forward to rotate the drum —34— and wind the cable —30— thereon thereby elevating the rear end of the frame —17— and shovel —1— to the inverted position shown by full lines in Fig. 4 and while in this position it may be automatically locked and temporarily detained by the catch —42—, until the driver has returned again to the place of excavation.

What I claim is:

1. In combination with the front and rear trucks of a vehicle, a reach-bar connecting said trucks and pivoted to the front truck, a tiltable shovel mounted upon the rear truck below the rear axle, means to tilt the shovel to and from its digging position, and a detent mounted on the rear truck and adapted to drop by gravity into holding engagement with the rear end of the shovel to prevent overturning of said shovel during the operation of loading.

2. In combination with the front and rear axles of a vehicle, a reach-bar pivotally connected to the front axle, an open frame beneath the rear axle secured to the rear end of the reach-bar, a shovel pivotally mounted upon said frame and tiltable vertically, and means to tilt said shovel to and from its digging position.

3. In combination with the front and rear axles of a vehicle, and wheels thereon, a reach-bar having its front end pivoted to the front axle and extending rearwardly therefrom, an open frame secured to the front end of the reach-bar, a shovel pivoted to said frame below the rear axle, a vertically rocking frame journaled in the wheels and connected to said shovel whereby the latter may be rocked upon its pivot to and from its digging position, a cable connected to the vertical rocking frame and a winding drum connected to the cable, and means for rotating said drum.

4. A wheel shovel comprising a front axle and a rear axle, and supporting wheels thereon, a reach-bar extending rearwardly from the rear axle and connected thereto, an open frame secured to the rear end of the reach-bar, a shovel pivotally mounted upon said frame below the rear axle, and means for tilting said shovel upon its pivot to and from its digging position.

5. In combination with the front and rear axles of a four wheeled vehicle, a reach-bar pivotally connected to the front axle, a shovel supporting frame secured to the reach-bar, a shovel pivoted to said frame to tilt vertically, means to tilt said shovel vertically to and from its digging position, and separate means to hold the shovel against overturning during the digging operation.

6. In combination with the front and rear axles of a four wheeled vehicle, a reach-bar pivoted to the front axle, an open frame secured to the reach-bar, a shovel pivoted to the open frame to tilt vertically, and means including a drum and cable for tilting said shovel upon its pivot.

7. In combination with the front and rear axles of a four wheeled vehicle, a reach-bar pivoted to the front axle, an open frame secured to the reach-bar, a shovel pivoted to the open frame to tilt vertically, means including a drum and cable for tilting said shovel upon its pivot, and means for engaging the shovel and preventing its overturning during the loading operation.

In witness whereof I have hereunto set my hand this 18th day of January, 1907.

CHARLES T. HOOKWAY.
